Primary Examiner — **Jae Liang**(74) *Attorney, Agent, or Firm* — **NZ Carr Law Office**(57) **CLAIM**

The ornamental design for an embossed cup, as shown and described herein.

DESCRIPTION

FIG. 1 is a perspective view of an embossed cup showing my design;

FIG. 2 is a front view thereof;

FIG. 3 is a left side view thereof;

FIG. 4 is a back view thereof;

FIG. 5 is a right side view thereof;

FIG. 6 is a top view thereof; and,

FIG. 7 is a bottom view thereof.

All broken lines represent portions of the embossed cup that form no part of the claimed subject matter.

In all embodiments, additional text, logos, graphics, or other surface elements could be present and superimposed on the design shown.

1 Claim, 7 Drawing Sheets(56)
